UNITED STATES PATENT OFFICE.

JOHN P. BENOIT, OF DETROIT, MICHIGAN.

BALANCED PISTON.

SPECIFICATION forming part of Letters Patent No. 352,293, dated November 9, 1886.

Application filed July 29, 1886. Serial No. 209,395. (No model.)

To all whom it may concern:

Be it known that I, JOHN P. BENOIT, of Detroit, in the county of Wayne and State of Michigan, having invented new and useful 5 Improvements in Balanced Pistons; and I do hereby declare that the following is a full, clear, and exact description thereof, reference being had to the accompanying drawings, which form a part of this specification.

10 This invention relates to certain new and useful improvements in pistons which reciprocate in horizontal cylinders; and the invention consists in the means employed for balancing the weight of the piston so that it will 15 equally bear on all sides, instead of bringing its weight to bear exclusively on the lower half of the cylinder, as is the case in all constructions of pistons in present use.

In the drawings, Figure 1 is a vertical central longitudinal section of my improved balanced piston. Fig. 2 is a cross-section thereof. Fig. 3 is a detached perspective view of one of the halves of a packing-ring.

A is the cylinder, B the piston-rod, and C 25 the piston, all of known construction, with the exception of the packing, which embodies my invention. This packing consists, essentially, of the packing-rings E, each ring made in halves, so placed around the piston that the 30 joints a between the ends of the halves of each packing-ring are in vertical line, or nearly so, with the center of the piston. Each half of the packing rings E is connected with the piston in such manner that the steam is thereby 35 cut off from the portion above such connection, without interfering, however, with the radial expansion thereof. This connection is made at or near the center of each half of the packing-rings, preferably above the horizontal center line of the piston, and to this end studs b 40 of the width of the packing-ring are secured to the halves of each ring and engaged into corresponding recesses, c, provided therefor in the body of the piston. By these means the 45 ring is detachable, and the studs cut off the steam-communication behind the upper and lower portion of the packing-ring, and around each of the packing-rings E is placed a packing-ring, F, of the ordinary description—that 50 is, one that acts by its own elasticity.

Steam-passages d are provided in the body of the piston, which lead from the steam-spaces of the cylinder to the back of each packing-ring, but only to the lower portion thereof,

as shown, the upper portion thereof being un- 55 provided therewith.

Suppose a piston of this construction to be used in a steam-engine, it will be seen that the steam will enter through the passages before described, back of the lower part of the piston-rings E, while it is cut off, or nearly so, from the upper part by the studs b, and it must therefore exercise a lifting action on the piston. This lifting action can be ascertained for a specific case and the parts so proportioned 65 that it will balance, or nearly so, the weight of the piston when in operation.

By practical experiments I have demonstrated the successful operation of the device, which has resulted in a large saving of power 70 and a greatly-diminished wear of the piston and cylinder.

What I claim as my invention is—

1. In a balanced horizontal piston, a piston-packing consisting of an inner and outer ring, 75 the inner ring being vertically divided and laterally connected with the piston, and of steam-passages leading back of the lower portion of the inner ring, substantially as described. 80

2. In a balanced horizontal piston, a piston-packing consisting of an inner and outer ring, the inner ring being vertically divided in halves, each half being laterally connected with the piston at a point above a horizontal 85 line through the center of the piston, and of steam passages in the piston terminating back of the lower portion of the inner ring, substantially as described.

3. In a balanced horizontal piston, a piston-packing consisting of an inner and outer ring, 90 the inner ring being vertically divided in halves, each half having a laterally-sliding connection with the piston in a horizontal line passing above the center of the piston, and of steam-passages in the piston leading back of the lower portion of the inner ring, substantially as described. 95

4. In a balanced horizontal piston, the combination, with the piston, of the two sets of 100 inner and outer rings, E F, the former being vertically divided in halves, and having studs b engaging into holes c of the piston, and of the steam-passages d in the piston, all arranged and operating substantially as described.
